SNOWMOBILE COWL

Elmer C. Kiekhaefer, Winter Haven, Fla., assignor to Brunswick Corporation, Chicago, Ill., a corporation of Delaware

Filed July 31, 1968, Ser. No. 12,974

Term of patent 14 years

Int. Cl. D12—13

U.S. Cl. D14—24

Fig. 1.

Fig. 2.

Fig. 3.

FIG. 2 is a front perspective view of the design; and
FIG. 3 is a front end elevation of the design.

The elements shown in broken lines are included for illustrative purposes only.

I claim:

The ornamental design for a snowmobile cowl, substantially as shown and described.
